UNITED STATES PATENT OFFICE.

EMIL J. BRACH, OF CHICAGO, ILLINOIS.

CONFECTIONERY-MACHINE.

1,348,081.

Specification of Letters Patent.

Patented July 27, 1920.

Application filed February 2, 1917. Serial No. 146,257.

To all whom it may concern:

Be it known that I, EMIL J. BRACH, a citizen of the United States, and a resident of the city of Chicago, county of Cook, and

5 State of Illinois, have invented certain new and useful Improvements in Confectionery-Machines, of which the following is a specification.

My invention relates to improvements in 10 confectionery machines of the type designed for use particularly in the formation of candy in special designs, such as in the form of peanuts, balls and other designs.

The object of my invention is the production 15 of a machine of the character mentioned which will be of durable and economical construction, and through the medium of which plastic material, such as molten candy, may be formed in the shapes 20 desired, readily and with great expedition, the operation being continuous.

A further object is the production of a machine as mentioned, in which the material introduced into position between the form 25 or mold elements of the machine will be positively confined in said form or mold members and prevented from being pressed or squeezed laterally therefrom.

Other objects will appear hereinafter. 30 With these objects in view, the invention consists in the combinations and arrangements of parts hereinafter described and claimed.

The invention will be best understood by 35 reference to the accompanying drawings forming a part of this specification, and in which,

Figure 1 is a side elevation of a confectionery machine embodying the invention,

40 Fig. 2 is a view similar to Fig. 1, with one side of the supporting frame removed and the shafts shown in section,

Fig. 3 is a horizontal section through the machine taken just above the lower series of 45 form elements.

Fig. 4 is a vertical transverse section taken on substantially line $x-x$ of Fig. 3,

Fig. 5 is an enlarged vertical section through the discharge end of the machine, 50 showing the relation and construction of the upper and lower sets of form elements.

Fig. 6 is a view similar to Fig. 5, illustrating one form of a construction for use in connection with the lower form elements to 55 eject the pieces of candy which have been formed therein,

Fig. 7 is a top plan view of one of the lower form members, the cams which co-operate with the confining members being shown in section, Fig. 8 is a section taken 60 on substantially line $y-y$ of Fig. 7,

Fig. 9 is a top plan view of one of the lower form elements, with the confining members omitted, and

Fig. 10 is a bottom plan view of a pair 65 of the confining members such as co-operate with each of the lower form elements.

The preferred form of construction, as illustrated in the drawings, comprises lower and upper supporting frame members 1 and 2, said frame members being adjustably connected at one end by a pin 3 which permits of pivotal movement of the opposite end of frame member 2, as will be readily understood. Pivotedly secured to a pin 4, provided at the opposite end of frame member 1, are connecting pins 5 which are adapted for engagement with a forked or recessed end portion 6 of the frame member 2. Helical compression springs 7 with which co-operate nuts 8, engage against the upper sides of end portion 6, serving to yieldingly hold the frame member 2 at its lower terminal of movement.

Mounted in each of the frame members 85 1 and 2, adjacent the respective ends thereof are transversely extending shafts 9 and 10 and 9' and 10', respectively. The shafts 9 and 9' are mounted in bearing blocks 11 which are shiftably mounted in elongated 90 slots 12 formed in the frame members 1 and 2, as clearly seen in Fig. 1. Adjustment of said bearing blocks in said slots is effected by means of screws 13 having swivel connection with said blocks at their inner ends, 95 the outer ends of said screws projecting loosely through the frame members 1 and 2 and having co-operating nuts 14 threaded upon the outer ends thereof.

Carried by the shafts 10 and 10' are meshing gears 15 and 15' respectively, the gear 15' being adjustably connected with the shaft 10', by mechanism, as clearly seen in Fig. 1, which permits of relative rotative shifting of said shaft in order to effect 100 proper registration of the form elements, as will be hereinafter described.

Carried by the shafts 9 and 10 are pairs of spaced alining sprocket wheels 16 and 17 respectively, as clearly seen in Figs. 2 and 4. 110 Carried by the shafts 9' and 10' are alining sprocket wheels 16' and 17' respectively.

Coöperating with the sprocket wheels 16 and 17 are two spaced sprocket chains 18 and coöperating with the sprocket wheels 16' and 17' are two spaced sprocket chains 18'. Arranged between and carried by the sprocket chains 18 is a series of form elements 19 which are arranged end to end and which have their inner ends fastened to said chains, as clearly seen in Fig. 4. The transversely elongated inner portion of each of the form elements 19 is rounded at its ends as at 20, as clearly seen in Fig. 8, in order to engage in the recesses between the teeth of sprocket wheels 16 and 17, as will be readily understood. The outer side of each of the form elements 19 is formed with a recess or mold 21 which is adapted to constitute one-half of the form or mold in which the candy or other plastic material is to be formed into the shape desired. Likewise carried by the chains 18' is a series of upper form elements 19' in the outer ends of which are formed recesses or molds 22. Said recesses or molds 22 are adapted to register with the recesses or molds 21 of the form elements 19, each pair, when in registering or operative relation, constituting a complete form or mold, as clearly seen in Figs. 5, 6 and 8.

In order to prevent pressing of the candy laterally from between the form parts through the meeting edges thereof, confining members 23 are provided which have their outer ends slidably mounted in grooves or channels 24 which are formed in the outer sides of form members 19, as clearly seen in Figs. 7, 8 and 9. The confining members 23 are secured in position by means of screws 25 which engage loosely with elongated slots 26 which are formed in the members 23 so as to permit of the desired lateral shifting or sliding of the same. The confining members 23 are normally held in outward position, or so that the inner ends thereof are out of engagement with the recessed portions of the form members by means of plungers 27 which are slidably mounted in recesses 28 formed in the sides of each form member 19, as clearly seen in Fig. 8. The plungers 27 are operatively connected with the confining members 23 by pins 29, helical compression springs 30 engaging with said plungers serving to press the same and hence the confining members 23 outwardly, as will be readily understood. The outer ends of confining members 23 engage against convergingly arranged elongated cam members 31, as clearly seen in Fig. 3, the arrangement being such that as said confining members, in the operation of the machine, approach the discharge end thereof, said confining members will be gradually moved toward each other or into close engagement with the sides of the form or mold forming portions of the members 19 and 19', so as to positively preclude the possibility of any

of the material which has been introduced into the forms or molds from being laterally pressed therefrom. The recesses or forms 21 are arranged end to end in the travel of the form elements between the sprocket wheels at the ends of the machine, and the confining members 23 are formed to completely inclose said recesses or forms, as clearly seen in Fig. 3.

The upper and lower series of form elements are so arranged that in the operation of the machine, the form elements at the adjacent sides of said series will gradually approach each other, the same being spaced a considerable distance apart at the left hand end of the machine, or as said form elements pass around the sprocket wheels 16 and 16', said form elements registering with each other in pairs, and gradually approaching each other until the sprocket wheels 17 and 17' are reached when said form elements are brought or pressed into close contact with each other, as clearly seen in Figs. 5 and 6. The adjacent sides of the form elements, that is the recessed portions thereof, which are thus brought into contact with each other, are knife-edged so that as said form elements are brought and pressed into engagement with each other, the candy or other plastic material contained in adjacent pairs of form elements will be completely severed from each other. In order to guide said form elements in this travel, guide bars 32 and 33 are provided for engagement with the sides or ends of the form elements 19 and 19', as clearly seen in Fig. 4. Said bars 32 and 33 are shouldered or channeled, in order to also prevent relative lateral shifting of the form elements in the travel of the same.

In order to effect ejection of the pieces of candy or other material from the form elements, as the form elements of the upper and lower series recede from each other, each of the lower form elements may be provided with a plunger 34 which is mounted in the bottom of each of the recesses 21. Coöperating with each plunger is a helical compression spring 35 which normally holds the same in retracted position, the spring 110 engaging with an end piece 36 carried at the inner end of each plunger. End pieces project from the inner ends of the form elements 19, for engagement with a stationary eccentric cam 37 mounted upon the shaft 10, said cam serving to push said plungers outwardly into the recesses 21 and thus serve to eject the pieces of candy or other material which may be seated therein, such ejection occurring, as will be seen, as said form elements recede from the upper form elements at the discharge end of the machine. The end pieces 36 are in threaded connection with the plungers 34, permitting of longitudinal adjustment of said plungers. 120 115 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

This adjustment of said end pieces is of special advantage in that it affords means for adjusting the position of the inner ends of said plungers relative to the periphery 5 of cam 37 so as to insure, at all times, proper engagement of said plungers with said cam, notwithstanding faulty assembly or wear to which said parts will be subjected in the operation of the machine.

10 In the operation of the machine, a strip of candy, or other plastic material to be operated upon, is fed into the left hand end of the machine between the form elements 19 and 19'. In order to regulate the size of 15 the strip thus fed into the machine, a pair of channel wheels 38 and 38' are provided adjustably secured by set screws 39 and 39' upon shafts 40 and 40' which are held stationary in a supporting bracket 41. The 20 channels in said wheels 38 and 38' are eccentrically arranged so that through rotative adjustment of said wheels, the operative depth of the channel may be varied and thus the size of the strip fed between the same 25 controlled, as will, of course, be readily understood. In the operation of the machine the strip of candy will be drawn past the members 38 and 38' by the form elements 19 and 19' in the travel of the latter. At 30 the opposite end of the machine is provided a discharge chute 42 into which the pieces of candy, or other material, are deposited after ejection from the form elements 19, as above described, the formation of the 35 pieces being, as seen, a continuous operation.

This machine is especially designed for use in the formation of candies having soft centers and hard shells. Up to the present time it has been a very difficult matter to handle 40 candy of this character inasmuch as it has been found that in pressing the outer shell or casing around the soft interior portion, portions of the latter would be squeezed out from the shell, which, of course, is very unsatisfactory. This difficulty has been occasioned primarily because of sudden forming or pressing of the casing around the soft interior, it having been found that in this 45 case the softer inner portion does not offer sufficient resistance to the outer shell, and consequently some of the inner portion is 50 squeezed laterally from the shell in closing the latter about the interior portion. With applicant's construction, however, wherein 55 the forming elements and the confining means approach each other very gradually,

it has been found that the above mentioned difficulty is overcome and that the outer shell or casing is pressed about the softer interior portion of the pieces of candy without any of the interior portion being forced out in the operation. 60

Driving of the machine is effected through the medium of a large gear 43 carried at one end of a transversely extending shaft 44 65 mounted in the frame member 1, a pinion 45 carried by said shaft, meshing with the gear 15 of the shaft 10, as clearly seen in Fig. 3.

While I have illustrated and described the 70 preferred form of construction for carrying my invention into effect, this is capable of variation and modification without departing from the spirit of the invention. I, therefore, do not wish to be limited to the 75 precise details of construction set forth, but desire to avail myself of such variations and modifications as come within the scope of the appended claims.

Having described my invention what I 80 claim as new and desire to secure by Letters Patent is:

1. The combination with a machine of the class described, of adjustable means for controlling the thickness of a strip of material 85 fed into said machine, said means comprising two coöperating rotatably adjustable wheels having eccentrically formed channels in the peripheries thereof; means for holding said wheels against rotation in the operation of the machine; and means for drawing the material between said wheels, substantially as described.

2. The combination with a machine of the class described, of adjustable means for controlling the thickness of a strip of material 95 fed into said machine, said means comprising two coöperating channel wheels, one of said wheels being rotatably adjustable and the channel thereof being eccentric; means 100 for holding said wheels against rotation in the operation of the machine; and means for drawing the material between said wheels, substantially as described.

In testimony whereof I have signed my 105 name to this specification in the presence of two subscribing witnesses.

EMIL J. BRACH.

Witnesses:

ARTHUR A. OLSON,
HELEN F. LILLIS.
